UNITED STATES PATENT OFFICE.

HARRY TUNSTALL, OF FAIRHAVEN, MASSACHUSETTS, ASSIGNOR TO ALSATIAN MACHINE COMPANY, OF BOSTON, MASSACHUSETTS, A CORPORATION OF MASSACHUSETTS.

DETACHING ROLL-MOTION FOR COMBING-MACHINES.

1,394,054.

Specification of Letters Patent.

Patented Oct. 18, 1921.

Original application filed October 7, 1918, Serial No. 257,089. Divided and this application filed October 29, 1919. Serial No. 334,227.

To all whom it may concern:

Be it known that I, HARRY TUNSTALL, a subject of George V, King of Great Britain and Ireland, residing in Fairhaven, in the 5 county of Bristol and State of Massachusetts, have invented a new and useful Improvement in Detaching Roll-Motions for Combing-Machines, of which the following is a specification.

- 10 In my application Serial No. 257,089 I have described in full a combing machine including the mechanism forming the subject-matter of this application, which is a division of the application above specified.
- 15 The main purpose of this mechanism is to give to the lower steel rolls a progressive oscillatory movement whereby with the assistance of the top or leather roll the fiber may be properly treated, and to give to the 20 leather roll a motion around the axis of the steel roll, *i. e.* the roll nearest the comb, so that it may grasp the tuft at the proper time and assist properly in the piecing up of the sliver. Heretofore the necessary motions have been given to these parts by cams 25 suitably cut and mounted. But I have found by experience that cams, although usual, are undesirable in machinery of this class, because the fiber is short and delicate 30 and any slight change in the movement of the parts operating upon it such as might be due to the wearing of the cam, changes the character of the product of the machine, and the wearing of the cams can only be remembered at considerable expense.

My invention will be understood by reference to the drawings in which it is shown in its preferred form, only so much of the whole machine being shown as is necessary 40 to indicate the mode of operation of the parts referred to.

Figure 1 is a front elevation showing the detaching roll, its top or leather-covered roll, and the means of applying power thereto.

Fig. 2 is a section on line 2—2 of Fig. 1.

Fig. 3 is a detail showing the mounting of the top or leather-covered roll.

Fig. 4 is an enlarged section on line 4—4 of Fig. 1, showing the clutch-operating mechanism.

Fig. 5 is a longitudinal section of the clutch, and

Fig. 6 is a front elevation thereof.

The purpose of the clutch is to give the necessary progressive oscillatory movement to the lower steel roll, moving it farther in one direction than in the other.

84 is the lower fluted steel roll which is mounted on the shaft 87 supported in bearings in the uprights A⁴, A⁵ shown in dotted lines in Fig. 1. On the shaft 87 is mounted the pinion 891 which meshes in the idler 90 on stud 91. The idler 90 is in mesh with the pinion 89 on the shaft carrying a second steel roll in the rear of roll 84 and hidden by it in Fig. 1, which meshes with the gear 92 on shaft 921 carrying the various members of the clutch, and is moved thereby. It and the top leather roll 86 receive the tuft. The clutch will be understood from Figs. 4, 5 and 6.

The gear 114 is suitably supported and is rotated by any suitable means such for example as is shown in my said application. A crank disk 1141 is mounted on the same shaft with gear 114 and carries a crank pin 120 which is connected by the link 115 to a pin 116, which connects together disks 117 and 118 forming part of the clutch. 119 are other pins which connect these disks. The location of the pin 116 is such that the radius of its movement is greater than the radius of movement of the pin 120 so that the rotation of the gear 114 will reciprocate the link 115 and oscillate the disks and the parts connected thereto.

On the shaft 921 is a sleeve 121 which carries fast thereon the ratchets 122 and 123. As shown, they are integral therewith and separated from each other to allow proper movement to the link 115. The disk 117 is mounted to turn freely on sleeve 121. A disk 124, of smaller diameter than disk 117, has a hub 121^a, which is adjustably fixed on shaft 921. The disk 124 is cut away as at 125 to expose for a portion of its periphery the teeth on the ratchet 123, while the periphery of the rest of the disk 124 extends slightly beyond the radius of the ratchet teeth on ratchet 123. On the hub 121^a is the disk 118, which is free to turn thereon.

The teeth of ratchets 122 and 123 point in opposite directions, and pawls 126 and 127 are provided, one of which engages ratchet 122 and the other the ratchet 123.

The pawl 127 is wider than the pawl 126 so as to overlap the disk 124. These pawls

are held to their work by springs 128 supported on sleeve 1281 mounted on one of the pins 119 connecting the disks 117 and 118.

It will be seen therefore that when the link 115 lifts (see Fig. 4), it moves the pawls, and the pawl 127 engages the ratchet 123 and pushes it in the direction of the arrow, the ratchet carrying with it the ratchet 122, 10 the sleeve 121 and the gear 92, which is keyed to the sleeve 121.

When the link 115 is pulled downward it reverses the movement of the pawls and consequently the pawl 126 engages and 15 moves the ratchet 122 and carries with it the sleeve 121 and gear 92 and also the pawl 127, which drags over the teeth of ratchet 123. But when the pawl 127 reaches the part of the disk 124 having the greater 20 diameter it rides up onto it (see Fig. 4), so that when the link rises again and the movement of the pin 116 is reversed, the pawl 127 moves first along the smooth surface of the disk 124 until it drops into the 25 teeth and gives motion to the ratchet, sleeve and gear. This disk 124 is adjustable on shaft 921 so that it will engage the pawl 127 at any desired time in its path of operation.

The result of this construction and operation is to give to the steel rolls an intermittent oscillating movement which is, however, progressive in that its movement in one direction is longer than its movement in the other, so that the fibers being properly retracted 30 will also be properly fed progressively forward in the piecing-up operation, and the amount of retraction may be adjusted according to the length of the fiber by adjusting the position of the disk 124 and consequently the time of engagement of the pawl 10 127 with the ratchet 123.

The position of the crank pin 120 may be adjusted in its slot in the crank disk 1141 to change the position of the link 115 so as 45 to adjust its throw and hence the path of oscillation of the parts connected to its upper end.

Power is applied to give the desired movement of the leather roll 86 as follows: The 50 shaft 8 which is suitably supplied with power from the power shaft (not shown) by means of the gear 7, etc. (see my said application), carries a disk 105, which is connected by a crank pin 106 and a link 107 to a rocker arm 55 108 by an adjustable slotted connection 109, the rocker arm 108 being attached to the shaft 103. 93 is the bearing for one end of the leather roll 86 (the other end of the roll being provided with a similar bearing 60 and mechanism), and it is mounted on the end of the spring 94, the rear end of which 65 engages the pin 95 on arm 97. A lever 96, also mounted on the arm 97, may be used 70 to adjust the tension of this spring 94 (see 75 Fig. 3). The arm 97 is mounted on a rock-

ing frame 101 which is hung on the shaft 87 so that it may be oscillated around it and so always maintain uniform pressure and contact between the leather roll 86 and the fleece which is carried over the steel roll 84. 70 The frame 101 is connected by the link 102 with the rocker arm 53 on shaft 103. The shaft 103 is mounted in suitable brackets supported by the uprights A⁴ and A⁵.

The operation and the theory of the above 75 mechanism will be understood by reference to my above application. I do not mean to limit myself to the exact mechanism above described, as it will be understood by those skilled in the art that the details may be 80 changed without departing from the spirit of my invention. I have only shown and described one side of the machine. It will be understood that so far as is necessary the other side of the machine is provided 85 with similar bearings, etc.

What I claim as my invention is:—

1. In a combing machine, a detaching mechanism comprising top and bottom rolls in engagement, and means for operating said bottom rolls whereby they are given an oscillatory movement, comprising a single shaft carrying oppositely-disposed ratchets, pawls adapted to engage said ratchets and move them in opposite directions and means whereby the movement in one direction will be longer than the movement in the opposite direction.

2. In a combing machine, a detaching mechanism comprising top and bottom rolls 100 in engagement, and means for operating said bottom rolls, said means comprising a clutch, one member of which is connected to one of said bottom rolls and, carrying oppositely-disposed ratchets, the other member 105 being oscillated to engage and oscillate said first member, and carrying pawls to operate said ratchets, and means adapted to lift and hold one of said pawls out of engagement with its ratchet for a portion of the time 110 during which the other pawl is moving its ratchet whereby said roll will be oscillated farther in one direction than the other.

3. As a means for oscillating and progressively rotating a roll, a reciprocating rod, 115 means for reciprocating it, a clutch one member of which is connected to said rod to be oscillated by it, the other member of said clutch being connected to said roll, and means comprising two oppositely-disposed ratchets and two pawls each adapted to engage one of said ratchets, for connecting said clutch members, and means adapted to hold one of said pawls out of engagement with its ratchet during a portion of its engaging movement whereby the rotary movement of one member will be longer in one direction than in the other.

4. As a means for oscillating and progressively rotating a roll, a reciprocating rod, 130

- means for reciprocating it, a clutch, one member of which is connected to said rod to be oscillated by it, the other member of said clutch being connected to said roll, and 5 means for connecting said clutch members whereby the rotary movement of one member will be longer in one direction than in the other, said means comprising two ratchets having teeth pointing in opposite directions, said ratchets being connected to said roll, and pawls adapted to engage said teeth whereby said ratchets will be oscillated together, said pawls being connected to said rod to be oscillated thereby, and means for holding one of said pawls out of contact with its ratchet during its oscillation in a 10 direction to engage said ratchet, said pawl being wider than its ratchet and its holding means comprising a disk concentric with said ratchet and having a portion of its periphery cut away to expose the ratchet teeth whereby said pawl may ride on part of the periphery of said disk out of engagement with the teeth of said ratchet. 15
6. As a means for giving to a roll a progressive oscillating movement, a clutch comprising a member connected to the roll to operate it and comprising ratchets with oppositely-disposed teeth and a second member and means for oscillating it, said second member comprising oppositely-disposed pawls, each located to engage its own ratchet and means to lift and hold one of said pawls out of engagement with its ratchet during a portion of its oscillation whereby the oscillation of said roll will be intermittent and its movement in one direction will be greater than in the other direction. 20 25

HARRY TUNSTALL.
